UNITED STATES PATENT OFFICE.

FRANK J. HINDERLITER, OF TULSA, OKLAHOMA.

SWIVEL BAILER TOP.

Application filed August 2, 1924. Serial No. 729,726.

This invention relates to a swivel bailer or the like adapted for bailing out oil wells and the like, and concerns itself primarily with the head construction thereof which 5 may also be used in connection with a sand pump or cleaning out pump, or for any other suitable purpose.

The invention comprises the novel structure and combinations hereinafter described 10 and more particularly pointed out and defined in the appended claims.

In the accompanying drawings which 15 illustrate a preferred embodiment of this invention and in which similar reference numerals refer to similar features in the different views:

Figure 1 is an elevational view of the bailer.

Figure 2 is an enlarged fragmentary longitudinal sectional view of the bailer. 20

Figure 3 is a view similar to Figure 2 but taken in a plane at right angles to the plane in which the section of Figure 2 was taken.

Figure 4 is an enlarged sectional view 25 upon the line 4—4 of Figure 3.

Figure 5 is a fragmentary sectional view through a modified form of bailer neck.

Referring to the drawings, the numeral 1 30 represents the body of the bailer, to which a novel form of head 2 is connected. This head consists of a cylindrical portion or neck 2^a provided with a bore 3 to receive the wire sand line 4. The inner portion of the bore 3 is counterbored for the reception 35 of a swivel head 5 which has an axial opening for the reception of the rope; said opening flaring toward its inner end to allow for spreading and securement of the sand line 40 therein.

The head 2 terminates at its other end in a pair of diametrically opposite and spaced attaching extensions 6 which are spread out beyond the diameter of the neck 2^a and form recesses at opposite sides of the head and the extensions have exterior arcuate surfaces corresponding to the interior contour of the bailer. The outer surfaces of these extensions are rabbeted to receive the bailer 1 which is secured to said extensions preferably by bolts or the like. These extensions are so formed and the upper end of the body portion of the bailer is so cut out as to form recesses in said portion which register with 50 the recesses in the head portion to provide suitable air apertures 7 between the said

extensions, said apertures 7 being large enough to insert the swivel head or its equivalent in place in the counter-bore of the neck. 60

In the use of this bailer, it is suspended from the sand line, and the swivel rotates and takes up the lay in the sand line, consequently the bailer will descend in a true vertical position. 65

In cases where a swivel connection is not necessary, the swivel may be removed and the sand line or cable secured in the swivel seat, or the bore in the head may flare inwardly as shown in Figure 5 to allow the 70 end of the cable to be wedged therein.

This novel form of bailer top or hood which is greatly reduced with respect to the bailer body has the advantage in that it can be more easily jarred loose if stuck and can 75 be more readily fished out by a combination socket and long stroke jar. The upper end of the head is preferably provided with serrations 2^b for this purpose.

It will be observed that the swivel head 5 80 lies entirely within its seat or counter-bore of the neck, only its inner edges being exposed and these edges being positioned beyond the apertures 7, so that no part of its circumference is exposed to gather grit and 85 lead it into the counter-bore or bearing for the head, which would soon grind the swivel head and its bearing away.

I am aware that numerous details of construction may be varied through a wide 90 range without departing from the principles of this invention, and I therefore do not purpose limiting the patent granted otherwise than necessitated by the prior art. 95

I claim as my invention:

1. A swivel bailer comprising a head having spaced extensions and a neck extending therefrom of reduced diameter, said neck having an axial bore enlarged at its inner end, a swivel head rotatably mounted in the 100 enlargement of the bore and a cylindrical body portion secured to the outside of said extensions and having that portion of its wall between said extensions notched to form recesses, the portion of the head at the junction of the neck and said extensions also forming recesses to register with body portion recesses to provide air openings on opposite sides of head to insert the swivel head 105 of the device. 110

2. A swivel bailer comprising a head having spaced extensions and a neck extending

therefrom of reduced diameter, said neck having an axial bore enlarged at its inner end, a swivel head rotatably mounted in the enlargement of the bore and a cylindrical body portion secured to the outside of said body portion secured to the outside of said extensions and having that portion of its wall between said extensions notched to form recesses, the portion of the head at the junction of the neck and said extensions also forming recesses to register with body por-

tion recesses to provide air openings on opposite sides of head to insert the swivel head of the device, said swivel head being located in the base of the neck with its inner edge lying outside of the bore and short of the air openings. ¹⁵

In testimony whereof I have hereunto subscribed my name.

FRANK J. HINDERLITER.
